US00D896195S

(12) **United States Design Patent** (10) Patent No.: **US D896,195 S**
(45) Date of Patent: **** Sep. 15, 2020**

(54) **VIDEO NETWORK CONFERENCE
TELEPHONE APPARATUS**

(71) Applicant: **YEALINK (XIAMEN) NETWORK
TECHNOLOGY CO., LTD.**, Fujian
(CN)

(72) Inventors: **Jian Cheng Zhang**, Fujian (CN); **Chun
Sheng Su**, Fujian (CN); **Jing Feng Su**,
Fujian (CN)

(73) Assignee: **YEALINK (XIAMEN) NETWORK
TECHNOLOGY CO., LTD.**, Xiamen
(CN)

(**) Term: **15 Years**

(21) Appl. No.: **29/626,121**

(22) Filed: **Nov. 15, 2017**

(30) **Foreign Application Priority Data**

Primary Examiner — Jeffrey D Asch

Assistant Examiner — Rebekah A Caruso

(57) **CLAIM**

The ornamental design for a video network conference telephone apparatus, as shown and described.

DESCRIPTION

FIG. 1 is a front, top, left perspective view of a video network conference telephone apparatus showing our new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof; and,

FIG. 7 is a left side elevational view thereof.

The broken lines illustrate portions of the video network conference telephone apparatus which form no part of the claimed design.

1 Claim, 7 Drawing Sheets
